UNITED STATES PATENT OFFICE.

ARTHUR J. MOXHAM, OF JOHNSTOWN, PENNSYLVANIA.

ROLLS FOR ROLLING GIRDER-RAILS.

SPECIFICATION forming part of Letters Patent No. 340,891, dated April 27, 1886.

Application filed February 13, 1886. Serial No. 191,879. (No model.)

To all whom it may concern:

Be it known that I, ARTHUR J. MOXHAM, of Johnstown, in the county of Cambria and State of Pennsylvania, have invented a new 5 and useful Improvement in Rolls for Rolling Side-Bearing Girder-Rails, which invention or improvement is fully set forth and illustrated in the following specification and accompanying drawing.

10 The object of this invention is to roll two finished shapes of side-bearing rails in the same set of rolls—that is, without changing the rolls for the production of either finished shape.

15 The invention will first be described as illustrated in the accompanying drawing, and then particularly set forth in the claims.

In the accompanying drawing is illustrated a set of rolls "three-high;" but they may be 20 "two-high," if preferred, containing seven "passes," numbered in their respective order, as shown, certain parts of each of said passes being designated by letters, as hereinafter described. Pass No. 4 is an edging pass, passes 25 Nos. 1 2 3 5 flattening passes, and passes Nos. 6 and 7 finishing passes.

The billet may be first reduced to shape suitable to enter pass No. 1 by rolling down in any ordinary or well-known grooves. The 30 section-lined space in the several passes shows like a templet the shape of the metal when leaving each individual pass.

The hot billet, having been first rolled through pass No. 1, is then successively rolled through 35 all the remaining passes (turned upon edge when put through pass No. 4) when it is desired to have a rail of cross-section indicated by the shape of pass No. 7; but if a rail be desired of a cross-section having the shape indicated by 40 pass No. 6 the rolling is stopped after putting the metal through said pass.

The operation of the several passes in effecting the desired changes in shape of the metal in the course of its rolling is as follows: In the 45 passes Nos. 1, 2, and 3 the "draft" is very heavy on the points a' d' , and on the part d , but lighter on the head part a . The excess of this difference in draft is put on the mass of metal in the earlier-shaping passes, when the 50 larger bulk of metal, and consequent greater rigidity and its short length, checks most of

the distortion which such excess of draft tends to effect, to such an extent that the guides used for leading the metal into and from the passes can prevent or overcome the small amount of 55 distortion remaining in the metal as it leaves said passes. In the edging pass, No. 4, the amount of draft put upon the parts e and e' is small, the excess of draft being put on the point b to reduce the same in thickness and 60 increase it in depth, the draft acting vertically through a' d' , and ample room for space of metal being provided at said point b . By the difference in draft proportioned herein the greatest change in the reduction of thick- 65 ness and increase of depth of web that is possible is effected, for only enough draft is put upon the rest of the mass of metal to permit of sufficient flow of metal to prevent buckling. Said amount of draft is at the same time, how- 70 ever, sufficient at these points to effect the desired change of form in the parts e and e' to suit them to enter the remaining passes. In passes Nos. 5 and 6 the part d is grooved out below the part e , which in pass No. 6 results 75 in a form of rail much used, wherein the side tram is provided with a lip or upturned edge, c . Pass No. 6 thus becomes, if desired, the finishing pass. In pass No. 7 the upturned flange or ridge c is rolled down and the rail is 80 discharged out of said pass with a flat side tram, as shown by the shape of said pass.

I do not limit myself to the upturned flange shown in passes Nos. 5 and 6, for if it is not desired to roll both forms of rail in one set of 85 rolls said passes can each be provided with a flush face, and thus the upturned flange c be entirely omitted from the rolling operation. Such change is, however, so small in its relation to the proportions of the remaining parts 90 of said passes that those skilled in the art can readily make such change without otherwise departing from the forms of said passes herein described; nor do I limit myself to but one edging pass—such as pass No. 4—as the desired change of form therein effected may be effected in two of such passes instead of but in one. This course would be advisable and preferable if only one of the two shapes of rails shown in passes Nos. 6 and 7 were de- 95 sired to be rolled in the same set of rolls, as by such repetition of edge-rolling one of the 100

flattening passes could be dispensed with, if desired.

Having thus fully described my said improvement in rolls for rolling side-bearing girder-rails, as of my invention I claim—

- 5 1. A set of rolls for rolling metal rails, provided with passes, substantially as hereinbefore described, having the conformations indicated in the accompanying drawing by the numbers from 1 to 7, inclusive, substantially as and for the purposes set forth.
- 10 2. A set of rolls provided with finishing

passes, as indicated in the accompanying drawing by the Nos. 6 and 7, one or both, and with one or more edging passes, as indicated in the accompanying drawing by the No. 4, and with flattening passes having the conformations substantially as described, and indicated in said drawing, substantially as and for the purposes set forth.

ARTHUR J. MOXHAM.
